UNITED STATES PATENT OFFICE.

ALFRED SCOTT BUCHER, OF DECATUR, GEORGIA.

DESIGN FOR A TOY.

58,133.

Specification for Design. Patented June 14, 1921.

Application filed August 27, 1920. Serial No. 406,490. Term of patent 3½ years.

To all whom it may concern:

Be it known that I, ALFRED S. BUCHER, a citizen of the United States, and a resident of Decatur, in the county of Dekalb and State of Georgia, have invented a new, original, and ornamental Design for a Toy, of which the following is a specification, reference being had to the accompanying drawing, forming part thereof.

The figure is a perspective view of the toy showing my new design, which consists of the conventionalized representation of a camel standing upon a truck.

I claim:

The ornamental design for a toy, substantially as shown.

ALFRED SCOTT BUCHER.
